(57) **CLAIM**

I claim the ornamental design for a duffle bag, as shown and described.

DESCRIPTION

FIG. 1 is a perspective view of a duffle bag.

FIG. 2 is a top view of the duffle bag of FIG. 1.

FIG. 3 is a bottom view of the duffle bag of FIG. 1.

FIG. 4 is a rear view of the duffle bag of FIG. 1.

FIG. 5 is a front view of the duffle bag of FIG. 1.

FIG. 6 is a left side view of the duffle bag of FIG. 1.

FIG. 7 is a right side view of the duffle bag of FIG. 1.

FIG. 8 is a view of the duffle bag with the flap and zipper open; and,

FIG. 9 is another view of the duffle bag with the flap open and the zipper closed.

The broken lines illustrate the environment and form no part of the claimed design.
